TOY SAVINGS BANK

Herbert Stone, New York, N. Y.

Application November 22, 1948, Serial No. 149,748

Term of patent 3½ years

(Cl. D34—11)

To all whom it may concern:

Be it known that I, Herbert Stone, a citizen of the United States of America, and a resident of the city of New York, in the county of New York and State of New York, have invented a new, original, and ornamental Design for a Toy Savings Bank, of which the following is a specification, reference being had to the accompanying drawing, forming a part thereof.

Fig. 1 is a side view of a toy savings bank with mouth closed showing my design,

Fig. 2 is a bottom view thereof,

Fig. 3 is a side view of a toy savings bank shown in Fig. 1 with the mouth in open position and showing the change in the position of the eye, and

Fig. 4 is a front view thereof.

I claim:

The ornamental design for a toy savings bank, substantially as shown.

HERBERT STONE.
